UNITED STATES PATENT OFFICE.

JESSE C. CHISHOLM, OF DALLAS, TEXAS, ASSIGNEE TO THE CHISHOLM PROCESS OIL REFINING COMPANY, OF DALLAS, TEXAS, A CORPORATION OF TEXAS.

PROCESS OF MAKING LARD SUBSTITUTE.

1,114,963.

Specification of Letters Patent.

Patented Oct. 27, 1914.

Application filed October 8, 1912. Serial No. 724,634.

To all whom it may concern:

Be it known that I, JESSE C. CHISHOLM, a citizen of the United States, residing at Dallas, in the county of Dallas and State of Texas, have invented certain new and useful Improvements in Processes of Making Lard Substitute, of which the following is a specification.

This invention relates to processes of producing culinary fats and has particular reference to a new and useful process of producing a lard substitute from cotton seed oil.

I have discovered that a lard like fatty composition suitable for use as a culinary fat can be produced from cotton seed oil by subjecting it to the action of a catalytic agent, preferably nickel or palladium or an alloy thereof in the form of wire or wire coatings, in the presence of hydrogen.

In the practice of my process I may advantageously employ the apparatus shown in the accompanying drawing forming a part of this specification wherein—

Figure 1 is a central longitudinal sectional view thereof, Fig. 2 is a cross-sectional view through the central or revolving portion of the apparatus, taken at right angles to Fig. 1, Fig. 3 is a view similar to Fig. 2 but showing a modified form of apparatus, and, Fig. 4 is a cross-sectional view taken at right angles to Fig. 3.

In the drawings 1 designates a closed cylindrical chamber or casing, preferably mounted upon suitable fixed supports 2 and provided with a pressure gage 3, a gas outlet 4 which may be set to discharge the gas at any desired pressure, a gage 5 to indicate the height of the liquid contents of the chamber 1, and a valve outlet for the finished product. Centrally and rotatably mounted within the chamber or casing 1 is a catalyzing element 7, preferably consisting of a spool-like support 8 containing strands of wire formed of or coated with a catalytic agent or an alloy thereof, the strands of the wire being spirally wound layer upon layer from the center outwardly, the wound mass being sufficiently porous to permit of the passage of liquid and gas outwardly therethrough, the liquid gas tending to follow the spiral course of the wire in its passage outward.

In the construction of the catalyzing element referred to, I may advantageously employ No. 20 copper wire with a rough black

unpolished electrolytic deposit of nickel thereon, although I may employ as a catalyzing agent, wire of nickel, palladium or other suitable catalyzing material which has been roughened and which is unpolished, or copper or other metallic wire coated with an unpolished film or coating or with a film or coating of an alloy of a catalyzing material, or the wire may have permanently deposited thereon the catalyzing agent as a finely divided powder or I may employ the catalyzing agent in the form of a finely divided powder permanently deposited upon a metallic wire coated or covered with the catalyzing element.

Within the spirally wound wire is a central chamber 10 with which there is rigidly connected at one side thereof an inlet pipe 11 to provide hydrogen gas from a suitable source of supply. To the other side of the chamber 10 is rigidly connected a pipe 12 which is in communication with an oil tank 13 adapted to contain the cotton seed oil to be treated. Pipes 11 and 12 are rotatably mounted within bearings 14 secured, as shown, upon opposite sides of the chamber or casing 1 and the pipe 12 is provided with a pulley 14' adapted to be driven by a suitable belt (not shown) connected with any desired source of power. Tight packing joints 15 are employed to connect the revoluble portions of pipes 11 and 12 with the fixed or rigid portions thereof. Outside of the bearings 14 I provide suitable stuffing boxes to insure a gas tight closure around the pipes 11 and 12.

Instead of employing the wire constituting or coated with the catalytic agent in the form of strands, I may employ woven wire in the form of wire gauze, fine mesh wire screen, or the like, as shown more particularly in Figs. 3 and 4.

While the proportions of the parts illustrated may be widely varied, satisfactory results may be obtained by forming the outer chamber or casing 1, three feet-six inches in diameter and six inches thick with inlets at opposite sides thereof of one-half inch. The catalytic agent 7 may advantageously have a diameter of twenty-three inches and a thickness of five and three-fourths inches, the inner chamber 10 being approximately three inches in diameter.

The catalyzing element is revolved in a direction to throw the liquid and gaseous

contents of the chamber 10 outwardly along the lines of the spirally wound wire so that in the rotation of the element 7 the mixture of cotton seed oil which enters through the pipe 12, preferably through a spray-nozzle 17 and hydrogen gas which enters through the pipes 11, is forced gradually outward by centrifugal action or by pressure, is brought intimately in contact with the wires of the catalytic agent.

10 I may advantageously introduce the hydrogen gas and oil under pressure, and I preferably employ the oil at a temperature of 160° C.

15 In the use of the apparatus, the cotton seed oil is placed in the tank 18 and is sprayed into the chamber 10 at a temperature of 160°. Hydrogen gas either in the form of hydrogen gas alone or with other 20 gases in water or producer gas, preferably Mond producer gas, is forced into the chamber 10 through the pipe 11 and is thoroughly mixed with the oil in the chamber 10. The catalytic element 7 is rotated rapidly in a direction to force the oil and hydrogen spirally outward along the lines of 25 the wire forming or coated with, the catalytic agent and in this contact the cotton seed oil undergoes a chemical change, where- 30 by its consistency is increased, a lard-like composition resulting from the change which takes place. This lard-like composition collects in the lower portion of the chamber or casing 1 and may be drawn off 35 and cooled, after which it is ready for the market.

40 The consistency of the finished product depends upon the length of treatment, the more slowly the revolution of the catalytic element, the more solid will be the finished product.

45 From the foregoing it will be evident that I have provided a continuous process for producing a lard-like fatty composition from cotton seed oil and that in the practice of my process, I am able to produce a fatty composition having any desired consistency, by regulating the rapidity of rotation of the catalytic element.

50 While I have described the preferred practice of my process, it will be evident that such practice may be variously modified without departing from the spirit of the invention or the scope of the subjoined claims.

55 Having thus described my invention, I claim:—

1. The herein described process of producing a lard substitute from oils, which consists in causing the oil to travel in engagement with a wire surface catalytic agent, in the presence of hydrogen, so that

the wire surface catalytic agent offers frictional resistance to the oil.

2. The herein described process of producing a lard substitute from oils, which 65 consists in causing the oil to travel spirally and outwardly in engagement with a spirally wound wire structure having its outer surface in the form of a catalytic agent, in the presence of hydrogen, so that the catalytic agent offers frictional resistance to the oil.

3. The herein described process of hydrogenating fatty material, which consists in causing the fatty material to travel by centrifugal force outwardly through curved 75 passages having catalytic agent walls, in the presence of hydrogen so that the catalytic agent offers frictional resistance to the fatty material for a protracted period.

4. The herein described process of hydrogenating fatty material, which consists in causing the fatty material to travel in a film by centrifugal force over a spiral catalytic element, in the presence of hydrogen 85 so that the spiral catalytic element offers frictional resistance to the fatty material.

5. The herein described process of hydrogenating fatty material, which consists in causing the fatty material to travel spirally by centrifugal force in engagement 90 with a catalytic agent, in the presence of hydrogen.

6. The herein described process of hydrogenating fatty material, which consists in 95 subjecting the fatty material while traveling outwardly by centrifugal force through longitudinally curved passages, to the action of hydrogen, in the presence of a catalytic agent.

7. The herein described process of hydrogenating fatty material, which consists in causing the fatty material to travel in a film by centrifugal force over a catalytic element embodying longitudinally curved contiguous strips, in the presence of hydrogen, so that the catalytic element embodying the contiguous strips offers frictional resistance to the fatty material.

8. The herein described process of hydrogenating fatty material, which consists in causing the fatty material to travel outwardly by centrifugal force in substantially horizontal longitudinally curved paths, in the presence of a catalytic agent and hydrogen.

In testimony whereof I affix my signature in presence of two witnesses.

JESSE C. CHISHOLM.
